(57) **CLAIM**

I claim the ornamental design for a control panel for AC/DC power supply, as shown and described.

DESCRIPTION

FIG. 1 is a front perspective view of a control panel for AC/DC power supply showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front end view of the control panel for AC/DC power supply in accordance with my design, shown in its environment thereof.

The broken line showing of the faceplate body, the ventilation screens, and the handles in FIG. 8 view are for the purpose of illustrating environmental structure and form no part of the claimed design.
